UNITED STATES PATENT OFFICE.

JOSEPH M. SCHUTZ, OF CHICAGO, ILLINOIS, ASSIGNOR, BY MESNE ASSIGNMENTS, TO STROMBERG MOTOR DEVICES COMPANY, OF CHICAGO, ILLINOIS, A CORPORATION OF ILLINOIS.

SUCTION AIR CLEANER.

Application filed June 20, 1921. Serial No. 478,872.

To all whom it may concern:

Be it known that I, JOSEPH M. SCHUTZ, a citizen of the United States, and resident of Chicago, in the county of Cook and State of Illinois, have invented certain new and useful Improvements in a Suction Air Cleaner, of which the following is a specification.

My invention relates to improvements in methods and means for separating materials from a gaseous carrier and has special reference to improvements in air cleaners and the methods for eliminating dust from the air before it enters the carburetors of internal combustion engines.

The object of my invention is to produce a device for this purpose which shall be so constructed or made as to preclude the possibility of any dust which has once been separated from the air, being again picked up by the air; which shall be so simple in its construction that the manufacturing cost shall be a practical minimum; and which shall readily be attachable to conduits leading to the exhaust and the intake.

Another feature of importance relates to the construction of the tangential inlet passages which I employ, the arrangement being such that I am enabled to produce a ring 30 of tangential passages in an exceedingly simple and inexpensive manner and to provide an effective inlet guard screen for the inlets.

In addition to the above many other advantageous results are obtained by and are embodied in the particular embodiment of my invention as hereinafter described and particularly pointed out in the appended claims.

My invention will be more readily understood by reference to the accompanying drawings forming part of this specification and in which:

Figure 1 is a fragmentary side elevation of an internal combustion engine equipped with an air cleaner made in accordance with my invention;

Figure 2 is a top plan view of the air cleaner;

Figure 3 is a vertical, central, sectional view of the air cleaner on the line 3—3 of Figure 2;

Figure 4 is a horizontal sectional view on the line 4—4 of Figure 3;

Figure 5 is a bottom plan view of the upper cover member.

Figure 6 is a top plan view of the lower cover member;

Figure 7 is an enlarged fragmentary sectional view similar to Figure 4 of a joint or connection in the lower part of the air separator;

Figure 8 is a fragmentary, vertical, central, sectional view particularly showing the depending dust discharge nozzle and the vertically arranged ejector;

Figure 9 is a vertical sectional view on the line 7—7 of Figure 3 showing the connecting pipe clamped in position; and

Figure 10 is a horizontal sectional view of the sheet metal connection, at the lower 70 end of the air cleaner, taken on the line 8—8 of Figure 3.

This present invention is an improvement upon my invention as disclosed and claimed in my co-pending application, suction air 75 cleaner, filed in the United States Patent Office, November 19, 1920, Serial No. 425,073.

In said drawings, 1 represents an internal combustion engine of ordinary design having a suction intake 2 and an exhaust conduit 3. My improved suction air cleaner is designated generally by 4. It is provided with a central outlet 5 at its upper end adapted to be connected to the intake 6 of a suitable carburetor 7 which is interposed 80 between the suction air cleaner and the intake 2 of the engine. The air cleaner 4 is adapted to remove the dust from the air before the air enters the carburetor and I make use of the pressure of the exhaust of 85 the engine to remove the dust continuously from the air cleaner and for this purpose the lower part of the air cleaner is connected to the exhaust pipe 3 by a by-pass pipe 8.

The air cleaner 4 consists of a cylindrical 90 sheet metal casing 9 open at its upper end and having a conical lower end 10. The upper end of the casing 9 is connected to a head or cover device 11 which I provide with a plurality of tangential inlet passages 100 12 around its circumference. This head or cover member 11 is made up of a lower ring member 13 and an upper or cover member 14. The lower member 13 has a large central opening 15 which receives the upper 105 end of the casing 9 and is provided with an annular internal groove 16 into which the upper part of the casing 9 is formed to retain these two members rigidly together. This lower member is in ring form and rising 110

from the ring are V-shaped projections 17 which are best shown in Figure 6 and which cooperate with similar shaped projections 18 depending from the cover member 14 to form the plurality of tangential inlet passages 12. The upper member 14 has a central opening 19 for receiving a depending outlet member 20 which is provided with a suitable flange 21 for securing the outlet member upon the cover member 14 by bolts 22. This outlet member is usually provided with an elbow part 23 for connection to the intake of the carburetor. The two members 13 and 14 are adapted to be rigidly connected to each other in their proper relative positions by bolts 24 extending down to the projections 18 and thru the lower ring 13.

As the inlet passages are of relatively large size being in the device shown in the drawings approximately $\frac{1}{2}$ of an inch wide and one inch high, I provide a guard surrounding the tangential row of inlets to prevent the drawing in of large objects such as leaves, straws, etc., which might clog the interior openings of the device.

This guard 25 is in the form of a ring of sheet metal which is provided with a great many relatively small holes 26 thru which the air can readily enter and pass thru the tangential inlet passages 12. The holes 26 are sufficient in number to prevent any wire drawing of the air at this point. I preferably make the guard 25 of spherical form as shown to provide ample space between the guard and the projections 17 and 18 forming the inlet passages 12 to permit the entering air to flow freely to the inlet passages. To hold the guard 25 in its position, I provide the members 13 and 14 with annular grooves 27 and 28 at their outer edges and adjacent to the faces of the projections 17 and 18 forming annular shoulders 29 between which the guard ring 25 is received and clamped. In assembling the several members of the head member 11, the lower ring 18 having been secured to the cylindrical casing, the guard ring 25 is then placed in position and the upper cover member 14 is then placed in position within the guard ring and with its projections 18 alternating between the projections 17 on the lower ring and then the cover members are clamped tightly together with the bolts 24 securing the member 14 upon the member 13 and serving to permanently hold the guard ring 25 in position without other fastening means. Preferably the nozzle 20 projects through the cover member 11 and extends down a short distance into the upper end of the chamber 9, so that the incoming streams of air through the tangential inlets must pass downwardly into the chamber 9 in order to escape through the central outlet at the top.

65 The hopper or conical bottom 10 of the

chamber 9 ends at its lower end in a straight or cylindrical neck 30 and the free end of this neck is formed into an outturned narrow flange 31 for the purpose of connecting a suitable discharge nozzle to the lower end 70 of the hopper.

As the air is drawn into the device by the suction of the engine through the tangential inlets 12, the several streams entering in through these inlets are caused to 75 whirl with high velocity upon the cylindrical surface of the casing and are forced downwardly in the casing to the conical bottom carrying all dust and other materials which the air may be carrying with it down 80 to the bottom of the chamber where I arrange means for preventing the picking up of the dust again as the air travels to the center of the chamber and rises thru the chamber to the outlet. This means 85 comprises a conical baffle wall 32 which is arranged centrally within the conical hopper 10 and which is supported upon a cylindrical wall 33 preferably formed integral therewith extending down through the neck 90 30 of the hopper and of a smaller diameter providing a narrow cylindrical channel-like annular space 34 between the neck 30 and the cylindrical wall 33 into which the dust, carried down the surface 10 by the whirling 95 air, is forced.

As best shown in Figure 3, the wall 33 is longer than the neck 30 and the upper end 35 thereof rises higher in the conical hopper than the juncture of the conical hopper 10 and the neck 30 and the upper part of the wall 33 thereby forms a baffle to prevent the carrying inwardly of the dust which is forced down the conical wall by the whirling air and causing such dust to be forced 100 down to the bottom of the channel 34. The wall 33 is supported upon a horizontal flange 37 which is in the form of an annular flange extending outwardly from the lower end of the wall 33 and preferably formed 110 integrally therewith, the outer diameter of the flange 37 being substantially the same as the flange 31 on the lower end of the neck 30.

In the completed structure these flanges 115 are clamped tightly together by means of the upper edge 38 of a smaller conical delivery hopper 39 which extends down below the hopper 10. The upper edge 38 thereof is adapted to be formed tightly around the 120 outer peripheries of the two flanges 31 and 37 as best shown in Figure 7.

The conical hopper 39 forms the upper end of a depending delivery nozzle 40 which has a substantially parallel portion 41 immediately below the hopper 39 and which ends below the parallel portion 41 in a conical delivery nozzle 42 having a relatively small delivery opening 43 at its lower end. This nozzle 42 forms the inner member of 125

an ejector, the outer member being formed by a sheet metal casing 44 surrounding the nozzle and adapted to be mounted rigidly relatively thereto and having a nozzle 45 adapted to be connected with the pipe 8 for receiving pressure from the exhaust pipe of the engine. The casing 44 is provided with a downwardly extending delivery nozzle 46 which as best shown in Figure 3, is made in the form of a Venturi tube, having an elongated conical part 47 at its lower end and a shorter conical part 48 at its upper end, the neck 49 of the venturi being arranged substantially in the plane of the outlet opening 43 of the nozzle 42 and below the side connection 45 whereby the gases under pressure which enter the side connection from the exhaust pipe escape through the Venturi tube past the lower end of the discharge opening 43 and produce an exceedingly strong suction at this point.

To permit the collected dust to enter into the device below the baffling member 32 I provide circumferentially extending discharge slots 50 in the flange 37 and at the bottom of the ring-like collection space 34. The action of the air in the collector is to drive the dust down through these openings and as fast as it is driven down to the lower part of the device, it is drawn out through the discharge opening 43 by the suction set up in the discharge nozzle 40 by means of the exhaust gases which escape through the Venturi tube.

An important feature of my invention relates to the fact that it is non-clogging in its operation. Once the dust has been separated from the air it finds no horizontal support, shelf or projection upon which to accumulate. The projection of the dust through the slots in the dividing baffle, is in a downward direction through the vertically depending nozzle 42 to the outlet opening 43, there the dust is caught by the strong suction produced by the ejector and is driven downwardly through the expanding nozzle 47.

The connection 44 is preferably made of sheet metal and as best shown in Figures 8 and 9, I preferably make it of two parts or halves 51 and 52, the dividing plane between the two parts being a longitudinal central plane extending from end to end. In order to arrange this connection so that it can be readily clamped upon the cylindrical portion 41 of the discharge nozzle and upon the end of the pipe 8, I provide flat parallel flanges 54 and 55 on the parts 51 and 52 respectively in the angle between the parallel portion 41 of the nozzle and the connection 49 and which flanges are adapted to be clamped tightly together by bolts 56 and 57. The bolt 56 clamps the connection around the parallel portion 41 of the discharge nozzle and the bolt 57 clamps the

connection around or upon the adjacent end of the connecting pipe 8. As best shown in Figures 9 and 10 the longitudinal adjacent edges of the two parts of the connection are lock-seamed together as shown at 58. This construction lends itself to the production of the connection at a low cost out of sheet metal by the usual stamping processes.

The construction of the upper end of the device forming the tangential inlets by providing a terminating cooperating projections on the members 13 and 14 greatly facilitates the production of these tangential openings for the reason that the projections on each of these members are so far apart that they can be readily produced by the usual molding, casting or die-casting processes and they can be readily smoothed up or finished on account of the wide spaces between the projections on the individual members. In fact, in the preferred manner of production of the device, there is very little machine work as the members 14 and 15 are preferably die-cast and the other parts of the device are made out of sheet metal. The low cost at which the device can be produced in quantities results in a greatly extended field of use.

In a practical sense the pulsations of the suction of the air through the carburetor to the cylinders of the engine are opposed by the pulsations produced in the dust discharge opening by the successive discharges of the exhaust gases from the cylinders and consequently the suction pulsations of the air cannot effect or produce a lifting of the dust which has been separated from the air by the centrifugal action in the separating chamber, with the result that substantially 100% of the dust is removed from the air.

The form of dust ejector which I have shown and described possesses advantages which are unattainable by the use of the form of ejector heretofore in common use, viz: the form in which the pressure is supplied through the central smaller tube instead of surrounding this tube as I have arranged it.

By means of the exceedingly high velocity produced at the neck of the venturi, I am enabled to produce a suction pressure in the dust delivery tube which is from six to ten times more than could be produced by the former method. Furthermore by this arrangement I am enabled to produce, by means of the exhaust, a stronger suction for the dust delivery end of the cleaner than is produced at the air delivery end by the suction of the cylinders. This stronger suction or lower vacuum pressure assists in preventing the clean air picking up the separated dust.

My device is exceedingly simple in construction and installation and once installed requires practically no attention whatsoever,

the dust being continuously discharged from the collection chamber and the air passing free of dust through the carburetor into the intake of the engine.

5 As many modifications of my invention will readily suggest themselves to one skilled in the art, I do not limit or confine my invention to the specific details of construction herein shown and described.

10 I claim:

1. In a device of the kind described, a head comprising two opposed members, the head having an annular series of tangential inlet openings between said members, the circumferential defining walls of said openings extending alternately from said two members as and for the purpose specified.

2. In a device of the kind described, a sheet metal casing having a substantially cylindrical portion open at one end, a ring member secured to said end, a cover member of substantially equal external diameter with the ring member secured to same and spaced therefrom, projections on the ring member 20 extending into contact with the cover member, and alternately arranged projections on the cover member extending into contact with the ring member, said projections circumferentially spaced apart and adapted to 25 form tangential inlet openings between same.

3. In a device of the kind described, a dust separation chamber having a conical bottom ending into a cylindrical outlet, a guard member in the form of a closed topped cylinder of smaller diameter in said outlet, the upper end of the cylindrical wall rising above the cylindrical wall of the outlet of 30 said conical bottom thus forming a radial baffle.

4. In a device of the kind described, a dust separation chamber having tangential inlets at its upper end and a central outlet at its upper end, a conical bottom at its lower end, the conical bottom ending in a cylindrical outlet, a concentric cylindrical closed topped baffle in the outlet providing a narrow circumferential space between the cylindrical outlet and the baffle, and circumferential discharge outlets at the lower end of said space 45 through which, the separated material is adopted to be driven to a position beneath the baffle.

5. In a dust separation device, a chamber having tangential inlets at its upper end and having a central air outlet at its upper end, a conical discharge nozzle for the dust at its lower end, a perforated baffle between its ends through which the separated dust is driven by the whirling air, and a Venturi 55 tube surrounding the discharge nozzle, means for supplying gas under pressure to the Venturi tube above said nozzle to produce a strong suction through the nozzle for removing dust through same.

6. In a device of the kind described, a

sheet metal connection in the general form of a T connection, the connection comprising two sheet metal parts joined on a longitudinal medial plane passing thru all three ends of the connection by lock seam joints, 70 said connection provided with opposed parts adapted to be clamped together by bolts for closing two of the ends of the connection upon cylindrical members as and for the purpose specified.

7. In a device of the kind described, a dust separating chamber, a depending dust discharge nozzle therefor and a vertically arranged ejector tube surrounding the discharge nozzle and having a depending discharge nozzle.

8. In a device of the kind described, a centrifugal dust separating chamber having a suction outlet at its upper end, said chamber having a conical lower end down 85 which the dust is projected by the centrifugal action, a slotted baffle in the lower part of the chamber through which the dust is projected, an elongated vertically disposed conical dust outlet nozzle below 90 the baffle, and a pressure ejector surrounding the outlet for producing a suction therein.

9. In a centrifugal separator, a substantially central air outlet at the upper end, 95 a ring of tangential inlets surrounding the outlet, a conical lower end depending from the ring of inlets, a substantially horizontal baffle closing the lower end of the cone, the baffle having dust escape openings at its 100 outer edge, a cylindrical wall rising in the chamber within said openings, and means connected with the cone below, said baffle for removing the dust therefrom.

10. In a device of the kind described, a conical dust collecting chamber, the lower part thereof having a cylindrical portion terminating in a conical nozzle, a sheet metal Venturi tube connection member adapted to be secured to said delivery nozzle 105 and adapted to be clamped to the said cylindrical portion thereof, said connection having a split cylindrical upper end provided with outwardly extending flanges at the split to be bolted together to clamp the connection in place, said connection formed with a side opening immediately below the upper flanged end and adapted to be clamped upon a connecting pipe for supplying gas under pressure to said venturi, said flanges 110 being formed to receive clamping bolts for this purpose.

11. In a device of the kind described, a dust separation chamber having a suction outlet at its upper end for air and a suction outlet at the lower end for dust, the dust suction outlet depending vertically, a venturi below the dust outlet in substantially axial alignment therewith, the delivery end of the dust outlet being 115

- smaller than and terminating at the neck of the venturi, and means for supplying hot gas under pressure to the upper end of the venturi as and for the purpose specified.
- 5 12. In a dust separation device, a circular chamber having a tangential inlet at its upper end for dust laden air and having an air outlet at its upper end, a conical discharge for the dust at its lower end, a per-
- 10 forate baffle between its ends through which the separated dust is driven by the whirling air, a Venturi tube surrounding the discharge nozzle, means for supplying gas under pressure to the Venturi tube
- 15 above the outlet of said nozzle to produce a strong suction through the nozzle for removing the dust through same.
13. In a device of the kind described, a chamber having a tangential inlet at its upper end for dust laden air and having an air outlet at its upper end, a vertical depending discharge nozzle for the dust at the lower end of said chamber, a Venturi tube surrounding said nozzle, means for supplying hot gas under pressure to said venturi to heat said nozzle and to cause a strong suction through the nozzle, as and for the purpose specified.
14. In a centrifugal separator, a sub-
- stantially central air outlet at the upper 30 end, a ring of tangential inlets surrounding the outlet, a conical lower end depending from the ring of inlets, ending in a substantially cylindrical lower end, a baffle wall closing said cylindrical part, said 35 baffle having a ring of dust escape openings adjacent to its edge, a cylindrical wall rising within said ring of openings and extending from the baffle to a point above the upper end of said cylindrical part, and 40 means connected with the cylindrical part below said baffle for removing the dust from the device.
15. In a device of the kind described, a dust separation chamber having a tangential 45 inlet at its upper end for dust laden air and having an outlet at its upper end, the chamber having a conical bottom terminating in a discharge nozzle, a pressure chamber surrounding the nozzle, the pressure chamber 50 having an annular outlet surrounding the discharge end of the nozzle, and means for forcing hot gases into and through the chamber and through said annular outlet.

Signed at Chicago, Illinois, this 20th day of May, 1921.

JOSEPH M. SCHUTZ.
